[57] **CLAIM**

The ornamental design for a jacket-type coaster, as shown and described.

DESCRIPTION

FIG. 1 is a front top perspective view of a jacket-type coaster showing my new design;

FIG. 2 is a side elevational view thereof, the broken line showing of a beverage can being illustrative of environment only;

FIG. 3 is a top plan view thereof;

FIG. 4 is a bottom plan view thereof; and

FIG. 5 is a rear elevational view thereof.

The side opposite that shown in FIG. 2 is a mirror image thereof.
